UNITED STATES PATENT OFFICE.

JOHN L. NICHOLSON, OF CHICAGO, ILLINOIS, ASSIGNOR TO LOCOMOTIVE FIREBOX COMPANY, OF CHICAGO, ILLINOIS, A CORPORATION OF DELAWARE.

THERMIC SIPHON FOR LOCOMOTIVES.

Application filed February 21, 1922. Serial No. 538,411.

My invention relates to improvements upon, or more accurately speaking, a modification of the so-called Nicholson thermic siphon, which is described and claimed in 5 U. S. Letters Patent No. 1,337,720, granted April 20, 1920. The original thermic siphon is made by folding the sheet from end to end over a mandrel or the like, which gives the siphon a bottom line which is substantially straight from end to end. My present 10 purpose is to provide a thermic siphon which shall make it possible to provide a given firebox with a greater sum total of heating surface than is possible with the siphon in its original form. To accomplish this purpose I depart from the original method of 15 siphon formation and truncate the upper rear end of the siphon, giving it at that point, a gently curved upward direction to 20 meet the crown sheet of the firebox. This and other features of my invention will be readily understood on referring to the accompanying drawings; and in which:

Figure 1 is a vertical longitudinal section 25 of a locomotive boiler containing one or more thermic siphons embodying the present invention; Fig. 2 is a vertical cross section thereof on the line 2-2 of Fig. 1; Fig. 3 is a top view of the firebox; Fig. 4 is an enlarged sectional view substantially on the 30 irregular section line 4-4 of Fig. 1; Fig. 5 is a side view of the portions shown in Fig. 4; Fig. 6 is a top view thereof.

It will be understood that it is the practice to apply thermic siphons to locomotive 35 fireboxes of all kinds and sizes. They are intended to increase the heating surface of a firebox and to cause a great circulation of water in the boiler, the extent of such circulation being dependent upon the firebox 40 temperature and the area of the heating surface presented by the siphon. In designing thermic siphons for fireboxes of short lengths and relatively great depth, a strictly 45 triangular form cannot be maintained in the firebox and yet secure all of the added heating surface that is desirable. By this present invention I overcome that difficulty.

In Fig. 1 the bottom line of the standard 50 thermic siphon is represented by the dotted line 2, with which the full lines of the modified form should be compared. The bottom or bulging portion 3 of the thermic siphon 55 corresponds to the standard siphon. Likewise the front end or edge 5 of the siphon

corresponds in form to the flue sheet 6, of the firebox, but at the upper rear end of the siphon I depart from the usual form by there truncating the siphon upon the line 7, which merges with the bottom line 3' upon 60 a generously curved line 7'. This siphon is made by folding a single sheet, as above, but at both front 5 and back 7, the edges of the sheet are brought together and welded, as upon the lines 5' and 7''. These welded 65 lines persist in the top flange 8 of the siphon, as clearly shown in Fig. 3.

The gently curved rear corner 7' does not interrupt the upward and rearward flow of water through the siphon, (the water enters 70 through the siphon neck 4'), and hence any solids contained in the boiler water are swept upward and discharged through the top opening 4'' of the siphon. However, for greater assurance in the matter of keeping 75 that portion of the siphon clean, I prefer to employ, and here provide, a valved blow-off pipe 9, as well shown in Fig. 1, one end 9' of the same hanging within the rear end of the siphon in position to exhaust any 80 solids that may accumulate there.

As will be obvious to anyone skilled in the art, the welded joints or seams of the siphons should always be protected by closely adjacent rows of stay bolts 15, as best shown 85 in Figs. 1 and 5.

This invention is of an extremely simple nature, but of considerable importance in the practical results which may be obtained 90 through its employment.

Having thus described my invention, I claim as new, and desire to secure by Letters Patent:

1. A thermic siphon having an angularly disposed bottom portion and a substantially upright front end, the rear end of said siphon being truncated to extend substantially parallel with said front end and merging into said angularly disposed bottom portion in a curve of a desired radius. 95

2. A thermic siphon formed from a single sheet of material folded along a predetermined line to form an angularly disposed bottom portion and two parallel spaced side walls, the front and rear marginal parts of which are offset inwardly toward each other and are welded together to form substantially parallel front and rear ends of different heights. 105

3. A locomotive firebox comprising in 110

combination with a thermic siphon having an angularly disposed bottom portion and a substantially upright front end, the rear end of said siphon being truncated to extend 5 substantially parallel with said front end and merging into said angularly disposed bottom portion in a curved line, and a blow pipe having a leg within the siphon and arranged adjacent said truncated rear end 10 thereof.

4. A locomotive firebox embodying therein a thermic siphon having an inclined bottom portion and front and rear ends, the upper rear end being truncated and of a depth less 15 than that of the front end and merging with the bottom portion upon a curved line.

5. A thermic siphon having an upwardly and rearwardly inclined bottom, a substantially upright front end and a truncated 20 rear end which is disposed at an angle to the bottom and merges thereinto.

6. A thermic siphon comprising a flat tubular body having a substantially horizontal elongated open top and having an inclined closed bottom which merges into a 25 tubular neck, the front end of the body being substantially upright and the rear end thereof being relatively shorter than the front end and joining the bottom by a 30 rounded corner.

7. A thermic siphon comprising a flat tubular body having a substantially horizontal elongated open top and having a closed bulged bottom portion, which terminates in a tubular neck extension, the front 35 and rear ends of the body being closed and the rear end being shorter than the front end and merging into the bottom portion by a rounded corner.

8. A thermic siphon having an angularly 40 disposed closed integral bottom and a substantially upright front end, the rear end of the siphon being also substantially upright, said front and rear ends being closed by fastening together edges of the sheet, at 45 least in part, and said fastened edges of the rear end being of less extent than the fastened edges of the front end.

9. A sheet metal thermic siphon having a closed bottom and an open top the open top 50 being bounded by an integral flange, said siphon having a substantially upright front end closed by fastening together edges of the sheet, said fastened edges continuing into the top flange and the line of said fastened edge 55 portions in the flange extending at an angle to the longitudinal axis of the siphon.

In testimony whereof, I affix my signature.

JOHN L. NICHOLSON.
